G. W. HULSHIZER

FRICITION HEAD FOR RIFLE BARS

Filed Sept. 16, 1925

UNITED STATES PATENT OFFICE.

GEORGE W. HULSHIZER, OF STEWARTSVILLE, NEW JERSEY, ASSIGNOR TO INGERSOLL-RAND COMPANY, OF JERSEY CITY, NEW JERSEY, A CORPORATION OF NEW JERSEY.

FRICITION HEAD FOR RIFLE BARS.

Application filed September 16, 1925. Serial No. 56,567.

This invention relates to rock drills, but more particularly to a device for imparting rotative movement to the drill steel of a fluid actuated rock drill of the hammer type.

One object of the invention is to hold the rifle bar of a rock drill immovable so that the hammer piston and the associated rotative elements will describe a partial revolution when the piston travels in one direction and to insure instant and positive release of the rifle bar at the time the hammer piston starts to move in the opposite direction.

Another object is to construct a rotation device having a maximum bearing and wearing surface and which is sufficiently rugged to withstand the excessive shocks and strains to which devices of this character are ordinarily subjected.

Other objects will be in part obvious and in part pointed out hereinafter.

The invention consists of the combinations of elements, features of construction, and arrangement of parts having the general mode of operation substantially as herein-after described and more particularly pointed out in the appended claims and illustrated in the accompanying drawings, in which—

Figure 1 is a longitudinal sectional elevation of a rock drill showing the friction head in releasing position, and

Figure 2 is a view similar to Figure 1 showing the friction head in engaging position with the friction ring.

Referring to the drawings, the invention is shown embodied in a rock drill having a cylinder A, a front head B and back head C, which parts form the outer casing for the rock drill and are held in operative position by the usual side bolts (not shown). The cylinder A is provided with a piston D having a forward fluted extension E which operates slidably with a correspondingly fluted chuck nut F in the front end of the cylinder A. The chuck nut F is arranged rotatably within the cylinder and has at one end clutch teeth G which cooperate with similar clutch teeth H formed on a chuck part J to prevent relative rotation between said chuck nut and chuck part J. Frequently in drills of this type, the chuck is constructed of a single piece, but in this instance, a second chuck part K is employed

and is arranged in the front end of the front head B to receive a drill steel L and has interlocking teeth O which engage similar teeth P formed on the forward end of the chuck part J to prevent relative rotation between the chuck parts. The chuck part J also serves as a seat for an anvil block Q arranged slidably therein to transmit the blows of the hammer piston D to the drill steel L.

Pressure fluid for actuating the hammer piston D and other associated parts is admitted into the drill through a suitable connection R secured to the valve chest S and is controlled by a suitable throttle valve (not shown) having a throttle lever T. The distribution of the pressure fluid may be controlled by any suitable valve. In this instance a flipper valve U is indicated. The flipper valve U controls the admission ports V and W leading from the rear and front ends of the valve chest S to the corresponding ends of the cylinder A. The exhaust of pressure fluid from the cylinder A is effected through a free exhaust port X controlled by the piston D.

In order to impart rotative movement to the piston D and associated rotative parts, a fluted rifle bar Y cooperates with grooves Z formed in the piston to prevent relative rotation between said piston and said rifle bar. A back cylinder washer b forms a cover for the rear end of the cylinder A and also serves to centralize the rifle bar Y. Although the rifle bar Y is shown fluted it is to be understood that any suitable form of bar may be used which will prevent relative rotative movement between the bar Y and the piston, and which will cause the piston to describe a partial revolution during one or the other of its strokes.

In accordance with the present invention a friction ring c is arranged in the back head C and has a tapered bore d. The friction ring c may be secured in position in any suitable manner, as for instance, dowel pins, a key, or press fitted as indicated in the drawing. A chamber e is formed in the rearward part of the friction ring c and communicates with the rearward end of the cylinder A through a passage f. The rifle bar Y carries at its rearmost end a friction head g tapered to correspond with the taper of the friction ring c. The head g is preferably somewhat smaller than the bore d so that when said head is in the releasing po-

sition shown in Figure 1, a slight space *h* exists between the periphery of said head and the bore *d*. Communication between said space *h* and the atmosphere is provided by a port *j* formed in the friction ring *c*, a passage *k* in the back head *C*, and a port *o* extending from the passage *k* to the exterior of the back head *C*. In this instance the chamber *e* is also in communication with the port *o* through a small port or vent *p* formed in the rearward end of the friction ring *c* to provide for the escape of air compressed by the piston during its rearward stroke.

15 To the end that the head *g* of the rifle bar *Y* may be automatically forced into engagement with the tapered bore *d* of the friction ring *c*, a plurality of plungers *q* are arranged slidably in bores *r* and bear at one end 20 against the back cylinder washer *b*. Springs *s* are arranged in the bore *r* rearwardly of the plungers *q* to hold said plungers outwardly against the cylinder washer *b*.

The operation of the device is as follows: 25 In the position of the parts shown in Figure 1, a portion of the pressure fluid in the rearward end of the cylinder *A* will pass through the passage *f* into the chamber *e* and act against the rearward surface of the head *g*. In this way the head *g* will be forced downwardly or forwardly against the back cylinder washer *b* as shown in Figure 1. It will be seen that when the head *g* is in this position, it is out of engagement with the bore *d* and the head *g* together with the rifle bar may then describe a partial revolution as the piston *D* advances on its forward stroke. While the friction head *g* is being held free from the friction ring *c*, a portion 40 of the pressure fluid in the chamber *e* is exhausted to atmosphere through the ports *j* and *p*, the passage *k* and the port *o* to immediately reduce the pressure acting against the head *g* below line pressure. After the piston *D* uncovers the free exhaust port *X*, the pressure fluid remaining in the chamber *e* will be exhausted through the passage or passages *f*, through the cylinder *A* and said main exhaust port *X* to the atmosphere as 45 well as through the passages leading directly from the chamber *e* to the atmosphere.

Simultaneously with the exhaust of the pressure fluid from the chamber *e*, the springs *s* will force the head *g* into engagement with the tapered bore *d* of the friction ring *c*. When the piston starts on its rearward stroke, a slight turning motion is imparted to the rifle bar which causes the head *g* to more firmly engage the tapered bore *d*. 55 By thus holding the rifle bar stationary the piston *D* during its rearward stroke will move in a spiral direction about the rifle bar *Y*, and since the piston and the chuck parts are interlocked against relative rotative movement, the drill steel *L* is rotated to a 60

different cutting position for the succeeding blow of the piston.

The foregoing described device has been found to be unusually efficient in operation and possesses the desirable advantage of permitting the head *g* to slip within the tapered bore *d* when the drill steel becomes stuck in the drill hole. In such case the drill may be slightly withdrawn and the piston *D* may continue to reciprocate until the drill steel *L* has become loosened in the hole. After the drill steel *L* is again free to rotate, the drill may be advanced and the friction head *g* and other parts comprising the rotative element will again function in their normal manner. Another desirable advantage of this invention is that the wear which in the ordinary rifle bar head and associated parts is usually confined to a few rather small wearing surfaces, may be of a comparatively large area so that the life of these parts may render a long period of service as compared with the usual devices of this character.

I claim:

1. In a fluid actuated rock drill, the combination of a cylinder, a reciprocating hammer piston in the cylinder, a back head for the cylinder, a friction ring secured fixedly in the back head and having a tapered bore, a friction head rotatable and longitudinally movable in the friction ring, a rifle bar carried by the friction head and extending slidably into the hammer piston, spring pressed plungers in the friction head adapted to bear continuously upon some non-rotatable element of the drill for moving said head into frictional engagement with the tapered bore in order to hold the rifle bar against rotation during the rearward stroke of the piston, a pressure chamber in communication with the cylinder to receive pressure fluid for actuating the friction head out of engagement from the friction ring when the hammer piston starts on its forward stroke, and a passage in the friction ring to establish communication between the tapered bore and the atmosphere for preventing air compressed by the piston from unseating the friction head.

2. In a fluid actuated rock drill, the combination of a cylinder having a single free exhaust port, a reciprocating hammer piston in the cylinder controlling the exhaust port, a back head for the cylinder, a friction ring secured fixedly in the back head and having a tapered bore, a friction head rotatable and longitudinally movable in the friction ring, a rifle bar carried by the friction head and extending slidably into the hammer piston, spring pressed plungers in the friction head bearing against the cylinder back head and adapted to move the said friction head into engagement with the tapered bore for holding the rifle bar against rota- 120 125 130

tion during the rearward stroke of the piston, and a pressure chamber in the friction ring communicating with the cylinder to receive pressure fluid for holding the friction head free in the friction ring during the forward stroke of the hammer piston, and a passage in the friction ring to establish

communication between the tapered bore and the atmosphere for preventing air compressed by the piston from unseating the friction head.

In testimony whereof I have signed this specification.

GEORGE W. HULSHIZER.
